CLOSURE FOR COLLAPSIBLE TUBES

Joseph M. Hamilton, San Francisco, Calif.,
assignor of one-half to Ray H. Kistler, San
Francisco, Calif.

Application June 13, 1932. Serial No. 616,771

1 Claim. (Cl. 221—60)

This invention relates to collapsible tubes or containers for toothpaste and like semi-fluid material which is dispensed from a tube by collapsing the latter.

It is the principal object of the present invention to provide an exceedingly simple and inexpensive closure device for collapsible tubes which will readily permit dispensing of the material but will automatically close when the collapsing pressure on the tube is relieved.

In carrying the invention into practice, a diaphragm of flexible material is secured over the open nozzle of the tube. This diaphragm is formed with a slit normally maintained tightly closed by the inherent contractile characteristics of the material of which the diaphragm is formed. When pressure is applied to the contents of the tube by collapsing the latter, the elastic qualities of the diaphragm permit the slit to open to permit the discharge of the tube contents. When the pressure is relieved, the diaphragm contracts to normal position and causes closing of the slit.

One form which the invention may assume is exemplified in the following description and illustrated by way of example in the accompanying drawing, in which:

Fig. 1 is a fragmentary view of a collapsible tube showing the discharge nozzle thereof in section and fitted with my improved closure device.

Fig. 2 is a similar view showing the diaphragm expanded to permit discharge of the tube contents.

Fig. 3 is a fragmentary view in perspective illustrating the exterior of my improved closure.

Referring more particularly to the accompanying drawing, 10 indicates a collapsible container or tube. This tube is formed with a nozzle 11 which is cylindrical in form and which is exteriorly threaded so as to receive a cap 12. This cap is formed with a concentric opening 14 which is in alignment, of course, with the axis of the nozzle 11.

Arranged intermediate the cap 12 and the outermost end of the nozzle 11 is a circular diaphragm 15 formed of rubber or any other suitable elastic composition. This diaphragm is of a diameter that its marginal edges may be clamped tightly between the adjacent surfaces 50 of the end of the cap 12 and the nozzle 11. It will be noticed that the center portion of the diaphragm is convex and projects slightly through the opening 14.

Formed centrally of this convex portion of the diaphragm 15 is a slit 16. The inherent elastic

qualities or characteristics of the diaphragm are such that this slit is normally maintained tightly closed. However, when pressure is applied to the contents of the tube, the convex portion of the diaphragm expands slightly to permit opening 60 of the slit 16 and consequently discharge of the material in the tube. When the pressure is relieved, the convex portion of the diaphragm contracts to normal position, closing the slit and sealing the nozzle.

When the tubes are filled and packaged for sale, a cork disk 17 is interposed between the diaphragm 15 and the end of the nozzle so as to prevent contact of the tube contents with the diaphragm until the tube is ready for use.

When the tube is ready for use, the cap 12 is removed from the tube by unscrewing it. The removable cork disk is removed from the cap and the cap is again applied to the nozzle as illustrated in Fig. 2. The tube is then ready for use.

As previously stated, by applying pressure to the contents of the tube by collapsing the latter, the diaphragm will expand and the material will discharge in a thin ribbon.

When the pressure on the tube contents is relieved, the diaphragm due to its inherent contractile qualities will assume a normal position closing the slit and thus sealing the nozzle.

Inasmuch as the convex portion of the diaphragm projects just slightly from the opening 85 14, it can be maintained perfectly clean and sanitary.

In actual practice I have found that this form of automatic closure for container tubes is very satisfactory and one of the main features of it 90 is that it is exceedingly inexpensive to manufacture. Also, it is highly efficient in operation and, while I have shown the preferred form of my invention, it is to be understood that various changes may be made in its construction by those 95 skilled in the art without departing from the spirit of the invention as defined in the appended claim.

Having thus described my invention, what I claim and desire to secure by Letters Patent is:

In combination with a tube of the character described, said tube having a cylindrical nozzle, said nozzle being exteriorly threaded, a cap having a cylindrical portion interiorly threaded whereby it may be threaded on the end of said 105 nozzle, said cap having a convexed end wall, said end wall of the cap having an enlarged opening formed centrally therethrough, the inner surface of the end wall of the cap adjacent the opening being rounded into a shoulder of uniform 110

slope, the outer edge of said opening being circular, a flexible diaphragm of even thickness over its entire area interposed between the cap and the nozzle end, the marginal edge of said diaphragm being adapted to be clamped between the cap and the end of the nozzle, the central portion of the diaphragm being sufficiently convex to nest within the opening in the cap and project just slightly beyond the exterior surface or end of the cap, said convex portion of the diaphragm being formed with a central slit normally being

80 maintained closed by the inherent elastic qualities of the diaphragm but capable of being opened by pressure applied to the tube contents, and an imperforate disk removably arranged in the cap intermediate the diaphragm and the nozzle, the marginal edge of the disk projecting between the cap and the edge of the nozzle so as to be clamped in position by the application of the cap to the nozzle.
